COMBINED GOLD SEPARATOR AND AMALGAMATOR

Jimmie L. Barber, 12606 Oaks Ave., Chino, Calif.
Filed Jan. 11, 1962, Ser. No. 163,523
1 Claim. (Cl. 209—42)

This invention relates to a combined gold separator and amalgamator that is so constructed as to be easily portable and usable as a means of recreation and sport, in particular vacation areas having bodies of water with sandy bottoms as in the ocean, lakes and the like. It is well known that in certain sections of the country there are bodies of water that are available to the vacationing public where the bottoms of lakes, oceans, and other bodies of water are known to contain small amounts of gold in the sandy bottoms, which may be pumped to the surface, separated and amalgamated so as to result in a low yield of gold.

The equipment heretofore used for such a process has been quite cumbersome and expensive. The purpose of the present invention however is to provide an inexpensive convenient and light weight portable unit for this purpose that will efficiently separate and amalgamate a sufficient amount of gold to stimulate an interest therein as a sport and at the same time to produce results of worth while value.

Although the primary object of the invention resides in the sporting and vacation use, it is to be understood that this portable unit may also be of some commercial value as a gold reduction means.

Notwithstanding the fact that certain objects of the invention have been set forth above, other features will become apparent as the specification proceeds and from the illustration in the drawings, in which:

FIG. 1 is a side elevational view of a combined gold separator and amalgamator.

FIG. 2 is a vertical longitudinal sectional view of the combined separator and amalgamator tank unit with portions being broken away; and

FIG. 3 is a transverse sectional view thereof taken on the line 3—3 of FIG. 2.

Referring now to the accompanying drawing FIGURES 1, 2 and 3 more in detail, the standard type of pump unit is generally designated by the character 1, the combined gold separator and amalgamator by the character 2, and the base member by the character 3.

The essential feature of novelty of my invention resides in the fact that due to the compact type of construction the device may be easily transported to the site where it is to be used; the pump unit 1 and the combined separator and amalgamator unit 2 being mounted on a base 3 with carrying handles 7 detachably fastened to the sides of the base 3 by clamping members 8.

When not in use the pick-up member 6 and the tubing 5 is wrapped around the entire assembly, but during the operation of the device the member 6 is contacted with material at the bottom of the body of water and this water

2

and sand is pumped by the pump 1 through the pipe and valve 4 into the inner coiled pipe 9 continuing through the outer coiled pipe 10 and discharged at 10a. The coiled pipe 9, 10 is provided with openings 11 to allow the passage of gold containing sand and other fine material during the pumping operation to settle to the bottom of the separator tank of the unit 2. In preparation for amalgamation of the gold, mercury is introduced into the tank 2 through pipe 14 and when the bottom of said tank unit 2 is sufficiently charged, the amalgamated gold may be removed by means of the said access door 16.

During normal pumping operation, valves 4 and 17 are open and 15 is closed. The small particles of gold are emitted through the small holes in the coiled pipe 9, 10 thus resulting in a primary separation in the coil and a secondary separation in the tank. During a flushing operation the greatest mass of sand and other foreign material is washed from the tank and coil system, in much the same manner as in panning of gold. When the gold particles settle to the bottom of the tank, then they may be recovered therefrom.

Since convenient portability is an important feature of my invention it will be noted that the pump 1 may easily be disconnected from the amalgamator unit 2 at the inlet side of valve 4, and carried separate from the entire unit. With the pump removed the adjustable handle 13 may be moved to a point affording correct carrying balance. With the pump in assembled position adjustable handle 13 is readjusted to allow proper balance for carrying, or the handles 7 may be used for carrying purposes instead of the adjustable handle 13. Valves 4, 15 and 17 are closed when the device is not in use.

While I have shown and described certain specific forms of my invention in a preferred form, it is understood that varying changes and modifications may be made, as deemed desirable within the scope of the appended claim.

I claim:

40 In a pump actuated gold generator and amalgamator the combination comprising a standard portable suction pump connected by a valve and pipe to a perforated coiled tubing, the inlet end of said tubing being connected to the said pump by said valve and the outlet end of the said coiled tubing having a valve controlled outlet at the upper portion thereof, the said perforated coiled tubing being enclosed within a tank, the outlet end of said tank being provided with an access door for recovering the amalgamated gold, and a pipe in said access door for charging the tank with mercury, the top of the said tank being 45 provided with an adjustable handle, a common base for the pump and tank having removable handles on the sides thereof.
